COVER FOR COIN RECEPACLES

Charles C. Veale, West Chicago, Ill., assignor to
 Western Electric Company Incorporated, New
 York, N. Y., a corporation of New York

Application October 31, 1936, Serial No. 108,590

8 Claims. (Cl. 232—15)

This invention relates to covers for coin boxes or receptacles and more particularly to covers for coin receptacles of the type used in telephone coin collectors, such a receptacle being described, for example, in United States Patent 1,121,063, issued December 15, 1914, to W. O. Beck.

Cash receptacles used in telephone coin collectors are ordinarily furnished with a hinged cover which has an opening therein through which the collected coins pass into the receptacle. A sliding shutter is usually provided for closing the coin receiving opening. A projection carried by an extension of the shutter is adapted to engage with a portion of the coin collector housing when the coin receptacle is placed therein, this engagement being effective, when the receptacle is being inserted in the housing, to move the shutter to open position, and being effective, when the receptacle is being removed, to move the shutter to closed position. Means is ordinarily provided for automatically locking the shutter in closed position.

In accordance with the usual practice the empty coin receptacles are prepared for distribution at a central cashier's office. Before the cover is placed on the coin box the shutter locking means is set in "free" position, i. e., a position which allows the shutter to move to open position. The cover is then placed in position on the coin box and suitably secured thereto, for example, by means of a special seal. The receptacles are then taken by designated employees to be placed in the telephone coin collectors. As the receptacle is inserted in the housing the shutter is moved to open position as stated above and the locking means is ordinarily so arranged that before the receptacle is fully inserted, the locking means is tripped and moved into locking position. Now when the filled receptacle is later withdrawn the shutter is closed as above mentioned, the locking means then being effective to hold the shutter in closed position.

An object of the present invention is to provide coin receptacle covers of the above mentioned type with an inexpensive and reliable shutter locking mechanism having means permanently associated therewith for facilitating authorized manipulation thereof and adapted to effectively resist fraudulent tampering therewith.

In accordance with one embodiment of the invention, a coin receptacle cover of the type referred to is provided with a shutter locking mechanism comprising a ratchet adapted to be rotated by movement of the shutter to open or closed position, a spring pressed locking pawl

for cooperating with the ratchet to prevent opening movement of the shutter, and a hand lever mounted on the under side of the cover for releasing the locking pawl. A projection on the ratchet is effective, during movement of the shutter from closed to open position, for tripping the locking pawl to locking position. The locking pawl releasing lever is constructed and arranged so that when the cover is in closing position on the coin box, a side wall of the box is in the path of the lever and prevents movement thereof to release the locking pawl.

Other features and advantages of the invention will become apparent from the following detailed description when read in conjunction with the accompanying drawings, in which

Fig. 1 is a plan view of a coin receptacle cover embodying the invention, showing the shutter in its closed position, a portion of the upper wall being broken away to show the gear teeth on the shutter which engage a pinion for moving the ratchet of the locking mechanism which is contained in a separate housing in the lower wall of the cover;

Fig. 2 is a plan view of the cover showing the shutter in its closed and locked position, a portion of the housing being broken away to show the locking mechanism;

Fig. 3 is a plan view similar to Fig. 2, but showing the locking pawl releasing lever moved to the position wherein it is about to trip the locking pawl to its free position;

Fig. 4 is a plan view similar to Fig. 3, but showing the locking pawl in its free position, and the releasing lever returned to its normal position, the cover now being shown in closed position on a coin box and with the shutter about to begin its opening movement as the coin receptacle is inserted in the coin collector;

Fig. 5 is a plan view similar to Fig. 4, but showing the relative positions of the parts when the coin receptacle has been inserted into the coin collector to a point where the locking pawl is about to be tripped to its active position;

Fig. 6 is a plan view similar to Fig. 5, but showing the shutter in its fully opened position after the coin receptacle has been inserted in the coin collector, the locking pawl being in its active position;

Fig. 7 is a similar view showing the relative positions of the parts when the coin receptacle has been partially removed from the coin collector, the shutter being shown partly closed with the locking pawl in position preventing opening

movement but permitting further closing movement of the shutter, and

Fig. 8 is an enlarged fragmentary sectional view on line 8—8 of Fig. 4.

5 Referring now to the drawings, a coin receptacle cover 10 is shown which comprises a flanged outer plate 11 and an inner plate 12 secured together in spaced relation by rivets or otherwise. A coin receiving opening 14 is provided in the plates and the plates are spaced apart sufficiently to slidably accommodate therebetween a shutter plate 15 for closing the opening. The shutter is rotatably mounted on a pivot pin 16 extending between the two plates. 10 A formed U-shaped spring 18 serves to normally hold shutter 15 in closed position with respect to opening 14. One end of spring 18 presses against the shutter at 19 and the other end of the spring is attached to a pin 20 (Fig. 1) secured to the 15 under side of outer plate 11. An extension arm 21 of shutter 15 extends upwardly through an arcuate slot 22 in outer plate 11 and then laterally beyond the edge of the cover as shown.

The inner plate 12 is formed with a circular recess or depression 24 (Fig. 8) in its upper surface and an inverted cup-shaped housing 25 is fitted into the recess so that a closed chamber is provided for housing the shutter locking mechanism hereinafter described. The upper surface 20 of the housing 25 is flush with the upper surface of inner plate 12, as shown in Fig. 8.

On the upper surface of the housing 25 a pinion gear 26 is rotatably mounted, the pinion having an integral hub portion 27 rotatably journaled in the upper wall of the housing. This pinion meshes with gear teeth 29 on an arcuate extension 30 of the shutter. The hub 27 of the pinion projects into the housing 25 wherein the hub has fixed thereto a toothed wheel or ratchet 32. By this structure ratchet 32 is caused to rotate in a direction opposite to that of shutter 15 when the latter is opened or closed.

A substantially dynamically and statically balanced locking pawl 33 is pivotally mounted with 45 in the housing on a pin 34 projecting downwardly from the upper wall of the housing to the upper surface of inner plate 12. The locking pawl has two pairs of symmetrical radially projecting arms and one of the arms 36 is adapted to cooperate with the teeth on ratchet 32 to prevent opening movement of the shutter. A formed U-shaped spring 37 serves to bias the pawl 33 in whichever direction it may be rotated beyond the dead center position shown in Fig. 3. One end 50 of the spring fits into a V-notch in the end of locking pawl arm 36 and the opposite end of the spring extends into a V-notch in the side wall of housing 25.

In Fig. 2 the shutter is shown in the closed position and the locking pawl is shown in the locking position, i. e., in the position wherein locking pawl arm 36 cooperates with a tooth on ratchet 32 to lock the shutter in closed position. The spring 37 holds the locking pawl in locking position. The substantially dynamically and statically balanced design of the locking pawl effectively resists fraudulent attempts to release it from the locking position by twirling or striking the coin receptacle or otherwise subjecting it to sudden shocks.

A hand lever 40 is provided for rotating the locking pawl in a clockwise direction (Fig. 2) to release it from locking engagement with the ratchet. The hand lever is of angular form having a vertical portion 41 pivoted in the depressed

portion 24 of inner plate 12 and extending below the peripheral flange of the cover where it is provided with a horizontal L-shaped handle 42. The vertical portion 41 has formed on its upper end a finger or cam 43 which projects laterally into the housing 25 and is adapted to engage an arm 44 of locking pawl 33 to rotate the latter in a clockwise direction upon rotation of the hand lever counterclockwise from the position shown in Fig. 2 to the position shown in Fig. 3. This 10 releases locking pawl arm 36 from ratchet 32. As soon as the locking pawl is rotated by cam 43 beyond the dead center position, spring 37 becomes effective to bias the pawl in a clockwise direction against a fixed stop 45 on the inner surface of housing 25, as shown in Fig. 4. The hand lever may now be returned to its normal position, the spring 37 now serving to hold the pawl in its "inactive" or "free" position, i. e., a position which allows shutter 15 to move to open position. 15

Upon movement of the shutter from closed position to open position, ratchet 32 is rotated in a clockwise direction (Fig. 4) through the engagement of toothed portion 30 of the shutter with pinion 26. A projection 47 on the ratchet 20 is effective, during movement of the shutter to open position, to trip the locking pawl 33 from its free position shown in Fig. 4 to its active position shown in Fig. 6.

In Fig. 5 the parts are shown in their respective positions when the locking pawl is about to be tripped by the projection 47 on the ratchet. It will be noted that the shutter is now only partially opened. As soon as the pawl passes the dead center position, spring 37 becomes effective 35 to bias the pawl in a counterclockwise direction, pressing locking arm 36 against smooth portion 48 of the ratchet. The pawl is now in its active position, wherein it is held by the spring, but the shutter is permitted to continue its opening 40 movement since the locking pawl arm 36 is now free to ride on smooth portion 48 of the ratchet.

Upon movement of the shutter from its open position to its closed position, ratchet 32 is rotated in a counterclockwise direction. The 45 spring pressed locking pawl arm 36 first rides on smooth portion 48 of the ratchet and then on the toothed portion thereof. The locking pawl arm drops into engagement with each ratchet tooth, successively, as the shutter moves to closing position. It will be noted that the construction is such that the first tooth of the ratchet is engaged by the locking pawl arm when the shutter is only partially closed, after which opening movement of the shutter is automatically blocked 50 by either one of the ratchet teeth depending upon the extent to which the shutter has been moved toward the closed position (see Fig. 7).

The manner in which the shutter 15 is moved to open position with respect to coin receiving 60 opening 14 as the coin receptacle is inserted in the coin collector housing, is illustrated in Figs. 4, 5 and 6. A portion 53 of the guide rail which is attached to the coin collector housing is shown, the guide rail being provided with an aperture 54 in which the arm 21 of the shutter is positioned, as shown in Fig. 4, when the receptacle is placed in the housing. Then, as the receptacle is pushed back into position in the housing in the direction indicated by the arrow, arm 21 is prevented from moving by its contact with the rear edge of aperture 54 so that the shutter is, in effect, moved to open position (Fig. 6) with respect to coin receiving opening 14. Conversely, when the receptacle is being moved in the oppo- 70 75

site direction, that is, when it is being withdrawn from the housing, the shutter is, in effect, moved to closed position with respect to opening 14. The respective dimensions and arrangement of 5 the coin receptacle and the coin collector housing are such that it is impossible to insert the receptacle in the housing without first positioning the shutter arm 21 in the guide rail aperture 54.

Before the coin receptacle is inserted in the 10 coin collector housing, locking pawl 33 should, of course, be set in free position (Fig. 4) to allow shutter 15 to be moved to open position. This is accomplished by means of the hand lever 40, as above described. This hand lever, being a permanent part of the cover mechanism, eliminates 15 the necessity of employing a separate tool for resetting the locking mechanism. It will be obvious, also, that the hand lever, being on the under side of the cover, is not accessible when the cover 20 is in closing position on the coin box. Furthermore, the hand lever is so constructed and arranged that it cannot be operated to release the locking mechanism when the cover is in closing position on the coin box. This will be apparent 25 upon referring to Figs. 4 and 8, wherein the cover is shown in closing position upon a coin box 60, a portion of which is illustrated. It will be noted that the hand lever 40 projects into the receptacle and is so positioned with respect to the side 30 wall 61 of the coin box that the latter prevents movement of the hand lever sufficiently to release the locking mechanism, as is clearly illustrated in Fig. 3. Thus, unauthorized tampering with the shutter locking mechanism is effectively 35 prevented.

After the locking pawl has been set in the free position by the hand lever, as above described, the cover is placed on the coin box and sealed. The receptacle is then inserted in the 40 coin collector housing. As stated above, the shutter is opened as the receptacle is pushed into the housing. As the shutter moves to the open position, projection 47 on ratchet 32 trips the locking pawl from the free position shown in Fig. 4 to the active position shown in Fig. 6, 45 wherein it is held by spring 37.

As long as the coin receptacle remains in the coin collector housing, shutter 15 remains in open position and locking pawl 33 remains biased 50 in the active position shown in Fig. 6. Upon withdrawing the coin receptacle from the housing the shutter is moved to closed position, as above stated. Locking pawl arm 36 rides on the periphery of the ratchet as the latter is rotated 55 counterclockwise by the closing movement of the shutter. After the shutter has been partially closed and while continuing its closing movement, locking pawl arm 36 passes over the ratchet teeth, which become effective successively for preventing opening movement of the shutter. Upon reaching the completely closed 60 position the shutter is automatically locked by engagement of the locking pawl with the last tooth on the ratchet, as shown in Fig. 2.

65 After the coin receptacle has been removed from the coin collector housing, the seal is broken by an authorized person and the cover is removed from the coin box. Before the cover is replaced, the locking pawl is reset in free position as mentioned above.

What is claimed is:

1. A coin receptacle having a coin receiving opening therein, a movable shutter for closing said opening, a rotatable member geared to said shutter and having a series of spaced teeth, a

movable locking element for cooperating with any of said teeth to prevent opening movement of the shutter, said element being movable to either of two positions, means for holding the element in either of said positions, said element being effective to cooperate with the teeth on the rotatable member in one of said positions and being ineffective to cooperate with said teeth in the other position, and means on the rotatable member movable into operative engagement with 10 and effective for moving the locking element from the ineffective position to the effective position.

2. A coin receptacle having a coin receiving opening therein, a movable shutter for closing said opening, a ratchet geared to said shutter, a movable pawl for cooperating with said ratchet to lock the shutter in closed position, said pawl being movable to either of two positions, means for biasing the pawl in either of said positions, 15 the pawl being effective to cooperate with the ratchet in one of said positions and being ineffective to cooperate with said ratchet in the other position, and a projection on the ratchet movable into operative engagement with and effective for moving the pawl from the ineffective 20 position to the effective position.

3. A coin receptacle comprising a coin box, a cover therefor having a coin receiving opening therein, a movable shutter for closing said opening therein, a rotatable member geared to said shutter and having a series of spaced teeth, a movable locking element for cooperating with any of said teeth to prevent opening movement of the shutter, said element being movable to 30 either of two positions, means for holding the element in either of said positions, said element being effective to cooperate with the teeth on the rotatable member in one of said positions and being ineffective to cooperate with said teeth 35 in the other position, and means comprising a hand lever mounted on the under side of the cover for moving the locking element from the effective position to the ineffective position.

4. A coin receptacle comprising a coin box, a cover therefor having a coin receiving opening therein, a shutter on said cover for closing said opening, a movable member on said cover for locking the shutter in closed position, and a hand lever pivotally mounted on the under side of the cover for releasing the locking member, said hand lever being constructed and arranged so that movement thereof to release the locking member is blocked by a portion of the coin box when the cover is in closing position on the box. 55

5. A coin receptacle comprising a coin box, a cover therefor having a coin receiving opening therein, a shutter on said cover for closing said opening, a movable member on said cover for locking the shutter in closed position, and a hand lever pivotally mounted on the under side of the cover for movement in a plane parallel to the plane of the shutter for releasing said locking member, said hand lever having a portion projecting into the box adjacent a wall thereof, 60 whereby said wall prevents movement of the lever to release the locking member when the cover is in closing position on the box.

6. A coin receptacle comprising a coin box, a cover therefor having a coin receiving opening 70 therein, a shutter on said cover for closing said opening, a moveable member on said cover for locking the shutter in closed position, and means for releasing said locking member comprising a hand lever mounted on the under side of the 75

cover for movement in a plane parallel to the plane of the shutter, said hand lever being constructed and arranged so that movement thereof to release the locking member is blocked by a portion of the coin box when the cover is in closing position on the box.

7. A coin receptacle comprising a coin box, a cover therefor having a coin receiving opening therein, a shutter on said cover for closing said opening, a movable member on the cover for locking the shutter in closed position, and means for releasing said locking member comprising a lever on the under side of the cover and having a portion projecting into the box adjacent an

inner surface thereof, whereby said surface prevents movement of the lever to release the locking member when the cover is in closing position on the box.

8. A coin receptacle comprising a coin box, a cover therefor having a coin receiving opening therein, a shutter on said cover for closing the opening, and a locking member pivotally mounted on the cover for locking the shutter in closed position, said locking member being substantially balanced dynamically and statically, whereby accidental movement thereof is prevented.

CHARLES C. VEALE.
